UNITED STATES PATENT OFFICE.

WILLIAM H. GRINDLEY, OF CONGLETON, ENGLAND, ASSIGNOR TO WILLIAM S. PITCAIRN, OF NEW YORK, N. Y.

DESIGN FOR A COVERED DISH.

SPECIFICATION forming part of Design No. 27,742, dated October 19, 1897.

Application filed September 8, 1897. Serial No. 650,994. Term of patent 3½ years.

To all whom it may concern:

Be it known that I, WILLIAM H. GRINDLEY, a citizen of Great Britain, residing at Congleton, Cheshire, England, have invented a certain new and original Design for a Covered Dish; and I do hereby declare the following to be a full, clear, and exact description of the same, reference being had to the accompanying drawings, forming a part hereof.

10 Figure 1 is a top plan view of the covered dish embodying my design. Fig. 2 is a side view, and Fig. 3 an end view, of the same.

The following are the leading features of my design: The upper edge of the dish A and its cover B are oblong in shape. The cover is elevated at the center and provided with a handle. At each end it is composed of convex curves *c* and *c'* reversed at their ends *a* *a'* *a''*, where they meet the ends *b* *b'* *b''* *b'''* of the flatter convex curves *d* *d'*, which form the sides of the cover. Parallel to the edge of the cover are arranged a plurality of rows *s*, *s'*, *s''*, and *s'''* of convex scallops. At the meeting places of the reversed curves *c* *c'* and *d* *d'* are placed twig-like ornaments *e* *e'* *e''* *e'''*, each consisting of a main branch *f*, gradually losing itself in the body of the

cover, and two side branches, one of which, *f'*, is single and the other, *f''*, divided.

The body of the dish is provided with a handle at each end, and is composed of four panels narrowing at the bottom, toward which they retreat backward and downward to form the feet, separated by arches slightly decorated with embossed arboreal forms. The 35 panels are separated by leaf-like ornaments *o*, *o'*, *o''*, and *o'''*, (not seen in any of the figures,) each of which is branched at the top and gradually lose themselves downward in the body of the dish.

The top edge of the dish *h* is curved inwardly, is parallel to the cover, and is decorated with a plurality of rows *t*, *t'*, *t''*, and *t'''* of convex scallops.

What I claim as new is—

15 The design for dishes substantially as shown and described.

In testimony whereof I have signed this specification in the presence of two subscribing witnesses.

WILLIAM H. GRINDLEY.
